UNITED STATES PATENT OFFICE.

EDGAR W. BROWN, OF DAYTON, OHIO.

DESIGN FOR AN AIR-DEFLECTOR FOR ELECTRIC FANS.

SPECIFICATION forming part of Design No. 31,899, dated November 28, 1899.

Application filed October 30, 1899, Serial No. 735,813. Term of patent 7 years.

To all whom it may concern:

Be it known that I, EDGAR W. BROWN, a citizen of the United States, residing at Dayton, in the county of Montgomery and State 5 of Ohio, have invented and produced a new and original Design for an Air-Deflector for Electric Fans; and I do declare the following to be a full, clear, and exact description of the same, reference being had to the accompanying drawings, forming a part thereof.

Figure 1 is a top plan view of an air-deflector for electric fans made in accordance with my design. Fig. 2 is an elevation of the same.

As shown in the drawings, the leading or 15 material features of my design consist of a shell or hollow case the upper or small end of which presents a circle, while the lower or large end of which is flaring and consists of two series of shields or alternating inner and 20 outer deflecting-surfaces. The shell A in elevation has the form of a truncated cone the

body of which is slit upwardly from the lower end at uniform spaces to provide two series of deflecting-shields B and C. The former occupy uniformly outer positions and are 25 concavo-convex, the concave surface being outward. The adjacent shields C have similar concavo-convex forms, but occupy inner uniform positions. The curvatures of the shields B are in line with and continue from 30 the upper end of the cone, while those of the shields C extend in a similar manner, but occupy planes inwardly from the shields B.

Having described my invention, I claim—

The design for an air-deflector for electric 35 fans, substantially as shown and described.

In testimony whereof I affix my signature in presence of two witnesses.

EDGAR W. BROWN.
